UNITED STATES PATENT OFFICE.

HUBERT KRANTZ, OF BROOKLYN, NEW YORK.

ELECTRICAL PANEL-BOARD.

SPECIFICATION forming part of Letters Patent No. 705,850, dated July 29, 1902.

Application filed March 12, 1902. Serial No. 97,871. (No model.)

To all whom it may concern:

Be it known that I, HUBERT KRANTZ, a citizen of the United States of America, residing in the borough of Brooklyn, in the county of 5 Kings, State of New York, have invented an Improved Electrical Panel-Board, of which the following is a specification.

One great difficulty in the use of electrical panel-boards and switchboards, especially those put up in houses and other such structures, is that unskilled or careless attendants are liable to be harmed by coming in contact with live parts of the circuit in manipulating the switches or in renewing blown-out fuses.

15 The main object of my invention is to so construct a panel-board or switchboard that these troubles cannot occur.

In the accompanying drawings, Figure 1 is a transverse section of a panel-board embodying my invention. Fig. 2 is a face view of a part of the panel with the outer door open. Fig. 3 is a face view of one-half of the panel-board with the protecting-cover removed; and Fig. 4 is a sectional view on the line 4-4, 25 Figs. 1, 2, and 3; and Fig. 5 is a view of a modification.

In the drawings I have shown my invention as applied to a panel-board on the three-wire system; but it will be readily understood that 30 my invention may be employed on other constructions of panel or switch boards.

In the views, A is the insulating back plate, and B represents the sides of the panel-board, which when employed in a building or like 35 structure may have its front closed by a hinged or sliding door in any usual or convenient manner, although I prefer to construct the door with a fixed center part C over the bus-bars and cross-bars and hinged side doors C' and C' over the fuses and switches for the 40 branch circuits.

D, D', and D'' are bus-bars, and E E' cross-bars for the switch and fuse connections to the various branch circuits.

45 The switches themselves may be of any suitable or convenient construction—quick-break switches, slow-break switches, or push-button switches, for example. In the drawings I have shown a slow-break switch F, pivoted 50 to a post f' on the back plate and having an insulated actuating-handle f. In any case the current-carrying parts of the switch are

inclosed and protected by a cover-plate K, which I prefer to make of insulating material. The actuating-handle f for the switch 55 F passes up through an opening k in the protecting-plate. At the sides of the panel-board on the back plate are the usual binding-posts M, to which the branch wires are to be connected, and in connection with these posts 60 are spring-clips or other suitable contacts m, with which the movable current-carrying part of the switch can make connection. In the case shown this movable part f'' is a pivoted lever-piece, whose plates can make connection with said clips m and also with spring-clips or other suitable contacts n on plates N. In the construction shown in Figs. 1, 2, 3, and 4 these connecting-plates N are mounted (preferably upon an insulating-partition P) at some distance away from the face of the back plate A and are provided with contact-clips n', which are arranged over or in front of clips e e' on the cross-bars E E', in order that I may provide for the insertion 75 and withdrawal of the fuses or fuse-cartridges into these pairs of clips substantially at right angles to the plane of the back plate. In the present instance I have shown these fuses as arranged between the switches and the cross-bars E E'; but the relative positions of these parts may be changed, provided the switches and fuse-clips are mounted upon the same back plate A with the bus-bars and cross-bars, or, in other words, all on the same panel, 80 and provided the current-carrying parts of the fuses, as well as the switches, are inclosed and protected by a cover or covers, such as K. It will be seen in Fig. 1 that the insulating cover-plate K extends over the fuses R, 85 holes r r', Fig. 2, being formed in the plate K for the ready insertion and withdrawal of the fuse-cartridges into and from the spring-clips n' on the plates N and the clips e e' on the ends of the cross-bars E E'. The partition P 90 also carries guides p (in the form of openings in a laterally-projecting part of the partition) for the guidance of the fuses. I prefer to make these fuses in the form of closed cartridges, as indicated, and for convenience and 95 protection of the person who may have to insert or withdraw them I prefer to provide them with insulating-handles r'.

In the modification shown in Fig. 5 I have

shown another form of fuse R', which will be inserted, by means of its handle r², into clips n² in a position parallel with the back plate, as will be understood.

5 By the constructions described I provide a panel-board which has its switches and fuse connections all mounted on the same back plate with the bus and cross bars, thus constituting a self-contained structure in which 10 the current-carrying parts of the switches and fuse connections are protected from harming the person who has to use them.

I claim as my invention—

1. An electrical panel-board, having a back 15 plate with conducting-bars and switches mounted on the said back plate, and a protecting-cover inclosing the said conducting-bars and the current-carrying parts of the switches and their connections, said cover 20 having openings for the manipulation of the switches.

2. An electrical panel-board, having conducting-bars, switches and fuses and contacts for the switches and fuses, with a protecting- 25 cover inclosing the said conducting-bars, switches and fuses and their contacts, said cover having openings for the insertion of the fuses and for the manipulation of the switches.

3. An electrical panel-board, having a back 30 plate, bus-bars and cross-bars with branch circuit connections and switches therein, all mounted on said back plate, and a protecting-cover inclosing all the current-carrying parts of the panel-board but with openings for the 35 manipulation of the switches.

4. An electrical panel-board, having a back plate, bus-bars and cross-bars with branch circuit connections and switches and fuses in 40 said branch circuits and a protecting-cover for all the current-carrying parts of the panel-board, but with openings for the insertion of the fuses and the manipulation of the switches, substantially as described.

5. An electrical panel-board having a back

plate and conducting-bars and switches thereon with pairs of fuse-clips, one clip of each pair being in front of the other to receive the fuse-cartridge substantially at right angles to the plane of the back plate, in combination with a protecting-cover for all the current-carrying parts of the panel-board, but with openings for the insertion of the fuses and the manipulation of the switches, substantially as described. 45

6. An electrical panel-board, having a back 50 plate and conducting-bars, switches and connecting-plates with pairs of fuse-clips, one clip of each pair being directly on the back plate and the other over or in front of the first to receive the fuse-cartridge substantially at 55 right angles to the plane of the back plate, in combination with a protecting-cover for all the current-carrying parts of the panel-board, but with openings for the insertion of the fuses and the manipulation of the switches, 60 substantially as described.

7. An electrical panel-board having a back 65 plate and conducting-bars with pairs of fuse-clips, one clip of each pair being over or in front of the other and a cover-plate for the 70 fuse-clips, said cover-plate having a hole for the insertion of the fuse-cartridge substantially at right angles to the back plate.

8. An electrical panel-board having a back 75 plate and conducting-bars with binding-posts having contacts on the back plate, and contact-plates at some distance from the face of the back plate, a switch having a pivoted current-carrying part to make connection with said contacts and a cover-plate with a hole 80 through which the switch can be manipulated.

In testimony whereof I have signed my name to this specification in the presence of two subscribing witnesses.

HUBERT KRANTZ.
